UNITED STATES PATENT OFFICE.

HERBERT M. STURGIS, OF HILLSBOROUGH, TEXAS.

COMBINATION-LOCK FOR MONEY-DRAWERS, &c.

SPECIFICATION forming part of Letters Patent No. 338,205, dated March 16, 1886.

Application filed May 16, 1885. Serial No. 165,749. (Model.)

To all whom it may concern:

Be it known that I, HERBERT M. STURGIS, of Hillsborough, in the county of Hill and State of Texas, have invented a certain new 5 useful Improvement in Combination - Locks for Money-Drawers, &c., of which the following is a full, clear, and exact description, reference being had to the accompanying drawings, forming part of this specification, and in 10 which—

Figure 1 is a perspective view of the inside of the drawer, showing my improved lock applied. Fig. 2 is a similar view of the bottom of the drawer. Fig. 3 is an enlarged detail 15 section taken on line 3 3, Fig. 1, showing the drawer unlocked, so it can be pulled out. Fig. 4 is a similar view showing the drawer locked in place. Fig. 5 is an enlarged top view of the part of the lock shown in Fig. 1, the top 20 of the housing being removed. Fig. 6 is a section taken on line 6 6, Fig. 5. Fig. 7 is a section taken on line 7 7, Fig. 5; and Fig. 8 is a section taken on line 8 8, Fig. 7.

My invention relates to a combination-lock 25 for money-drawers, &c., for store use; and my invention consists in features of novelty hereinafter fully described, and pointed out in the claims.

Referring to the drawings, A represents a 30 money-drawer, and B part of a store-counter or other support, to which the drawer is secured in such a manner as to be moved in and out to open and close it. Secured to the inner part of the drawer is the housing C of the 35 lock. Within the housing is pivoted a frame, C', by a rod or pin, C', the lower end of which is held, when in its normal position, toward the inner end of the drawer by a spiral spring or springs, C'. (See Figs. 4 and 8.) The frame 40 has a top rod or round, C', and a bottom bar or strip, C', to the former of which are hinged two or more bars, D, the connection preferably being made by slotting the inner ends of the bars to receive the rod, and then passing 45 pins D' through them (the rods) back of the round, as shown. The bars have hooks D' on their free ends, which may be made to project up or down, as desired, by taking out the pins D' and reversing the bars. When the drawer 50 is closed, these hooks enter between a lower jaw, I, and upper jaw, I', secured to the counter

or other support of the drawer. When the hooks are turned down, or those of them that are turned down, they engage the jaw I and prevent the drawer being pulled out until 55 they are raised, which is accomplished through means of vertical levers J, pivoted to the housing C by a rod, J', passing through horizontal extensions J'. There is a lever for each bar, and to the lower end of each lever is connected a rod or wire, L, that extends to near the front end of the drawer, (see Fig. 2,) where each is provided with a finger-piece, L', guided and held to the bottom of the drawer by a bracket, L', through which they can move 60 freely. By pulling on any one of these wires the corresponding bar D will be raised.

In practice part of the hooks of the bars would project downward and part upward, and the corresponding wires of all those that 70 project downward would have to be pulled at once to unlock the draw, as all the hooks will have to be raised from the jaw I before the drawer can be pulled out, and an unauthorized person would not know, without first 75 learning the combination, which bars to raise.

To make the lock still more secure and effective, the jaw I' is provided, so that every time a wrong bar is operated the hook of that bar will be lifted and engaged with this jaw, 80 so it will be seen that just the right bar or bars, according to how many hooks are turned down, and no other, must be operated to unlock the drawer; and with a number of bars (I have shown six) the lock is susceptible of a quantity 85 of combinations, and all that is necessary to do to change the combination is (as before stated) to reverse one or more of the bars by removing a pin or pins, D'.

I have shown the jaws I I' formed on a 90 bracket, I'. (See Fig. 1.)

The levers have projections J' on their lower ends, that come against the bar C' of the frame when the levers are pulled back, thus throwing the bars D forward slightly as they are lifted 95 by the levers, (see Fig. 3,) to prevent friction against the lower jaw. When the lower end of the frame is thus forced over by the operation of a lever or levers, it is restored, when the pressure is removed from the lever or levers, 100 by the spring or springs C', above mentioned.

When it is attempted to open the drawer

and a wrong bar or bars raised, the upper end of the frame will be pulled toward the inner end of the drawer by means of the hook of such wrong bar engaging with the jaw I'. 5 The consequence of this would be to force the lower end of the frame toward the front end of the drawer against the spring C³, and in doing this a projection, N', on a bar, N, hinged at N² to the frame, comes against a projection, 10 O', on the inner end of a hammer, O, pivoted at O² to the housing C, and pulls the hammer back to the position shown in dotted lines, Fig. 5, against the pressure of a spiral spring, O³, and as soon as the projection on the bar 15 passes the projection on the hammer, the hammer is pulled back by the spring and strikes a gong, P, giving an alarm without the drawer being unlocked. The hammer has another projection, O⁴, that supports the free end of 20 the bar and keeps it from falling.

I have shown the lower ends of the levers J projecting from the bottom of the drawer through an opening, A', the wires L being connected to the levers outside the drawer. 25 The opening may be covered by a shield, U, open in front for the passage of the wires, as shown.

I claim as my invention—

1. The combination, with the drawer and its support, of a pair of jaws, a plurality of bars having hooks turned in opposite directions for engaging said jaws, and operating levers and rods or wires for actuating said hook-bars, as explained. 30 2. The combination, with the drawer and its support, of the pair of jaws I I', the pivoted rods D, each having a hook, D², projecting from one side thereof, one or more of said hooks being presented toward each jaw, as ex- 35

plained, the finger-pieces L, and the connections between said finger-pieces and hook-bars, substantially as set forth. 40

3. In combination with the drawer and its support, the hinged reversible hook-bars, pivoted levers for raising the bars, wires or rods 45 for operating the levers, and jaws I I', all arranged and operating substantially as and for the purpose set forth.

4. In combination with the drawer and its support, the pivoted frame C', reversible hook-bars hinged to the frame, levers for raising the bars, wires or rods for operating the levers, jaws I I', bar N, pivoted to said frame, spring-hammer having a projection engaged by a projection on the bar, and a gong, all arranged 55 and operating substantially as and for the purpose set forth.

5. In combination with the drawer and its support, the pivoted frame C', having rod C⁴ and bar C⁵, hook-bars hinged to the frame, levers for raising the bars, projections J³ on the levers, for engaging the bar C⁵ of the frame, spring or springs C³, wires or rods L, and jaw I, all arranged and operating substantially as and for the purpose set forth. 60

6. In combination with the drawer and its support, the frame C', having rod C⁴, reversible hinged hook-bars secured to the frame by being slotted to receive the rods C⁴ and by pins D', pivoted levers for raising the bars, wires 70 or rods for operating the levers, and jaws I I', all arranged and operating substantially as and for the purpose set forth. 75

HERBERT M. STURGIS.
